CLAIM

The ornamental design for a paver stone, as shown and described.

DESCRIPTION

FIG. 1 is a perspective view of a paver stone showing my new design;

FIG. 2 is a bottom plan view thereof;

FIG. 3 is a top plan view thereof;

FIG. 4 is a first side view elevational view thereof;

FIG. 5 is a second side elevational view thereof;

FIG. 6 is a third side elevational view thereof; and,

FIG. 7 is a fourth side elevational view thereof.

The broken lines shown in FIG. 2 view are included for the purpose of illustrating a portion of the paver stone that forms no part of the claimed design.
